UNITED STATES PATENT OFFICE

ALVIN G. SHERMAN, OF GROSSE POINTE, AND ALBERT MEADOWS, OF DETROIT, MICHIGAN, ASSIGNORS TO THE DETROIT VAPOR STOVE COMPANY, OF DETROIT, MICHIGAN, A CORPORATION OF MICHIGAN

APPARATUS FOR ENAMELING METAL ARTICLES

Application filed February 26, 1927. Serial No. 171,356.

This invention relates to an apparatus for enameling metal articles, and has to do particularly with a novel apparatus for straightening and positively maintaining the so straightened articles between or after the firing operations or operation.

Heretofore, in applying enamel to sheet metal articles and the firing of such enamel-coated articles, it has been the practice to perform the several operations on the articles separately. The metal has been cleaned by giving it several baths in cleaning solutions; the work has been conveyed on trucks in stacked relation to a dip tank; the plates dipped and set upright without any relation to the subsequent firing or the preceding cleaning operations, and then stored on trucks preparatory to the firing operation. In the firing operation the enamel-coated articles have usually been placed on a suitable carriage in large gangs and fed into a muffle furnace and heated until they are in a dull red-hot condition. When the articles have been fired the proper length of time, according to the individual operator, they are then removed from the muffle furnace and transferred to racks or trucks and allowed to cool. This transferring of the pipes or articles to the racks from the firing operation has been manual and entirely dependent upon the individual operator. After a cooling operation, the trucks are wheeled to spraying booths preparatory to applying the finish enamel coats thereto and subsequently firing the same.

Recently a continuous enameling process and apparatus has been developed, such as is described in our copending application Serial No. 31,811, filed May 21, 1925, which has become Patent No. 1,681,441. In this recent process the articles are continuously worked in predetermined time periods, and synchronized from the time the process is first undertaken until it is finally finished. The various steps are coordinated in capacity, speed, and distance of travel so that they all work together to apply the several coats of glass enamel to the article as it travels in the line of instrumentalities. The articles are fired in a rotary electric furnace and the dipping, dipping, and drying operations are coordinated

with such firing furnace whereby the articles are in the proper physical and chemical conditions and are placed in the firing furnace at a predetermined time after the dipping and drying whereby to obtain best results in the firing operation. The articles are progressively and uniformly heated in the rotary furnace, and are taken out at a point closely adjacent where they are placed into the rotary furnace. These articles, when taken out of the furnace, are at a dull red heat, according to the particular firing operation carried out, and it has been the practice to place these articles, after being directly removed from the rotary furnace, on a suitable straightening plate. It also has been the practice for an operator to remove such articles from the straightening plate and place the same on a suitable cooling conveyer preparatory to inspection and initial finish-coat spraying. As this operation has been left entirely up to the particular operator, it has often resulted that the articles or plates were picked up too soon by the operator, with the result that a slight, or even a great warping or sagging resulted. Furthermore, plates or articles placed in upright positions for subsequent cooling have been subjected to still further warping or sagging, due to such vertically hanging, when transferred from the rotary furnace to the cooling conveyers too soon.

It is the object of the present invention to interpose a medium between the firing operations or after the firing operations, whereby the correct cooling and straightening of each and every article is positively insured. The apparatus comprises a suitable conveyer moving horizontally and longitudinally, and provided with links or conveying surfaces which are fairly close together and of relatively heavy material. This conveyer is positioned between the rotary furnace and the cooling conveyers, the one end being positioned adjacent the removal point of the rotary furnace, and the conveyer being of such length, and its other end being positioned adjacent the cooling conveyer, so that the red-hot articles being placed thereon will be properly straightened and cooled, and it will be impossible for the operator to remove the

articles from the conveyer until they are in the proper condition for handling. In other words, when the operator moves the articles from the straightening conveyer, or when they are automatically transferred to the cooling conveyer, they are in such condition as to positively eliminate any possibility of warping or sagging due to the heat imparted by the firing furnace.

10 In the drawings:

Fig. 1 is a diagrammatical view of a continuous enamel-coating and firing system, and showing in particular the positioning of the straightening and cooling conveyer between the furnace and secondary cooling conveyers.

Fig. 2 is a fragmentary detail view, somewhat diagrammatic, of a conveyer that may be used in carrying out this process.

20 It is believed that the invention will best be explained by describing the steps of operation leading up to the particular step forming the main basis for the present invention. Metal articles, particularly sheet metal articles, and even cast iron articles, have presented many difficulties in the glass enameling thereof, and a large majority of such difficulties, and a cause of the resulting imperfections, may be traced largely to the improper 25 chemical and physical changes which arise between the various operations. While the present invention may be utilized in various enameling systems other than the one described in applicants' above mentioned pending application, it is adapted to such a system 30 because it is a very important cog in obtaining uniformly perfect ware. Referring to Fig. 1, which is somewhat diagrammatic, the properly cleansed articles or plates may be 35 dipped in the tank 1, which is known as the ground coat dipping tank. After the articles are properly dipped they are immediately transferred to the conveyer 2. The details of this conveyer are fully described 40 and illustrated in applicants' said copending application, but it will be sufficient for the present invention to state that it is a timed conveyer adapted to receive and position the articles vertically.

45 A drying chamber is preferably provided for forcing the drying of the dipped articles, such drying chamber being designated 3. The conveyer for receiving the dipped articles is preferably positioned to run along closely 50 adjacent the one wall of the drying chamber as at 4. This run of the conveyer from the dipping tank to the drying chamber may be called the "dripping run". This dripping run portion and conveyer are so positioned 55 adjacent the drying chamber that the plates positioned on the conveyer will be subject to radiating heat from the drying chamber, so as to temporarily fix the depth of enamel coat at the proper time.

60 The drying chamber 3 assists in forcing

the drying of the articles, and is so designed and operated that the articles, after being dipped and having the proper coating-enamel, are dried to have the proper chemical and physical properties upon issuing from the drying chamber, thus eliminating all chances of damage to the coated surfaces due to the humidity of the air and dust or other particles. The properly dried articles continuously and successively issue from the drying chamber and are presented by the conveyer to a position 5 closely adjacent the feeding port of a firing furnace, which may be generally designated 6.

As such properly coated and dried articles 70 are continuously and successively presented, they must be removed by the workmen, and immediately placed in the firing oven. Each piece is therefore uniform with respect to physical and chemical characteristics at the 75 time it is to be fired, and each piece is therefore also fired at just the proper time after drying.

The rotary furnace 6 is diagrammatically 80 illustrated in Fig. 1, and it is of the type described in applicants' said above mentioned copending application. It comprises an electric furnace of circular design, the heating portion of which comprises an annular small 85 passageway extending around the furnace. In this annular passageway is adapted to rotate a suitable table provided with prongs 90 for receiving the articles to be fired. Suitable electric resistance elements are placed in the furnace at the desired point whereby the articles are progressively brought up to the desired fusing temperature, maintained at such 95 temperature for the correct amount of time and then progressively cooled until they reach a position to be removed from the furnace. 100 As this firing operation is uniform and continuous, each separate article fired will, at the time of its removal from the furnace, be of approximately the same temperature. In practice, such articles as are removed from 105 the rotary furnace, are of cherry red in color, and are of such a temperature that they very 110 easily warp and sag, particularly if the articles are large and have broad faces. The 115 articles are taken from their horizontal position on the supporting prongs in the furnace by means of forks which are designed to evenly support the articles at all points. However, this is not always possible, and it is 120 therefore sometimes desirable to lay the hot articles on a flat surface whereby they will straighten, due to the inherent heat in the article, and thus be in a condition to handle properly when cool. It may be that even if 125 the article warps the warped part may be brought into shape by subsequent firing operations, but this is not always true and it usually produces an imperfect article, if such article is warped or sags after the first firing 130 operation.

In order to positively prevent the article from being picked up too soon after it is removed from the firing furnace, a straightening conveyer is provided, which may be designated 7. This conveyer is supported at the ends by means of suitable gears or rotors 8, whereby the conveyer is continuously moved in a closed path at a desired speed. The length of this conveyer 7 is proportioned according to the firing temperature maintained in the furnace 6, one end of the conveyer being positioned closely adjacent the take-out aperture of the furnace, and the other end of the conveyer being positioned closely adjacent a conveyer 9, which may be termed a secondary cooling conveyer.

The articles, when they are removed from the furnace in their cherry red condition, are then placed flatly upon the straightening conveyer 7. This conveyer is provided with a plurality of heavy, flat, shoes or slats 10 which present a continuous flat surface between the rotors 8. As the hot articles are positioned flatly on this conveyer, they will gradually straighten out, due to their inherent weight and temperature, and also gradually cool. The separate articles are maintained in this flat condition the length of the conveyer and the conveyer is of such length that when said articles reach the end of the conveyer, they will have cooled to such an extent that they will not be affected in the least by the removal from the conveyer table by the operator. This positively eliminates all sagging and warping of the hot articles due to any operator picking them up too soon, and it automatically insures straightening of all the articles.

When the articles are removed from the straightening and cooling conveyer they are placed in upright position on the secondary cooling conveyer 9 and are conveyed back and forth whereby they are completely cooled, so as to be initially inspected and then conducted through the spray booth.

After the articles are sprayed they are immediately dried and fired, and then sprayed, dried and fired again for the finishing operation. It will be understood that between the second and third firing operations a similar conveyer 7 may be utilized for positively effecting straightening and cooling of the articles. The same is true after the final firing operation when the finally finished articles are stored or placed upon racks. After this final firing operation, the article may be placed directly on a cooling and straightening conveyer, just as is shown in Fig. 1, and therefore insuring positive straightening and the correct amount of cooling before being picked up and stored or transported.

It will be understood that the conveyer elements 10 are preferably heavy, whereby, in case any extra heavy sheet or article is fired and is slightly warped when placed upon the

straightening conveyer, that suitable weighting means may be utilized when effecting straightening of the article.

It will be also understood that this interposition of the straightening and cooling conveyer between the first and second firing operations cooperates directly with the spraying and subsequent firing operation, in that the articles are insured to be evenly and uniformly sprayed, as otherwise if the article were warped or sagged, it might not be uniformly sprayed. Furthermore, when the articles are placed in the rotary firing ovens for the second or third firing operations, it will be obvious that they might be so warped or might have sagged so that the subsequent firing operations would only accentuate the warped or sagged portion. By positively straightening and cooling the article between each firing operation the finished, a straightened uniform quality of article is obtained both as to the firing of the enamel and the contour of the surface.

Claims:

1. In an enameling mill of the type having a rotary furnace for consecutively firing metal articles at a relatively high heat and means for receiving the fired articles, the combination with said firing furnace and said receiving means of a conveyer positioned therebetween, one end of the conveyer being adjacent the outlet of the furnace and the other end adjacent said receiving means, the surface of said conveyer being relatively flat whereby to receive the hot fired articles and to straighten the same, the length of the conveyer between said furnace and said receiving means being such as to insure cooling and fixing of the straightened articles whereby to insure that the articles will not be affected when transferred from the straightening conveyer to the receiving means.

2. In an enameling mill for metal articles, the combination of firing means for firing and delivering metal articles at a relatively high heat, means positioned adjacent said delivering point for receiving and supporting said articles whereby they are straightened due to said supporting surface, means for moving said supporting means whereby movement of the supporting surface will simultaneously cool said article or articles thereon at or during the straightening step, and a secondary cooling means positioned adjacent said supporting means at such a distance from the delivering point of the hot articles to insure cooling and fixation of the articles before being transferred to said secondary cooling means.

In testimony whereof we affix our signatures.
